TURNTABLE

Frank C. Poyner, San Diego, Calif.

Application March 18, 1946, Serial No. 655,347

10 Claims. (Cl. 104—41)

1

My invention relates to a turntable for use in turning various vehicles substantially 180° and the objects of my invention are:

First, to provide a turntable of this class which is entirely automatically operated by the vehicle driven thereon.

Second, to provide a turntable of this class which is motivated by the traction wheels of the vehicle driven thereon in engagement with rollers thereof which are automatically locked against rotative movement after the vehicle in connection with my turntable has been rotated substantially 180° about the axis of the turntable, whereby the operating traction wheels of the vehicle move the vehicle from the rollers of the turntable and force the same off the turntable in the opposite direction of the original approach.

Third, to provide a turntable of this class which is very useful in turning trucks or the like when transporting earth and rocks from an excavation.

Fourth, to provide a turntable of this class having an automatic clutch operating lever, which is tripped when the turntable frame rotates relatively to the base, providing automatic reversal of the turntable frame at each successive operative movement thereof.

Fifth, to provide a turntable of this class in which the indexing latch in connection with the base is automatically disengaged from the turntable frame by the vehicle as it is driven upon the turntable frame.

Sixth, to provide a turntable of this class which is very simple and economical of construction, efficient in operation and which will not readily deteriorate or get out of order.

With these and other objects in view as will appear hereinafter, my invention consists of certain novel features of construction, combination and arrangement of parts and portions as will be hereinafter described in detail and particularly set forth in the appended claims. Reference is had to the accompanying drawings and to the characters of reference thereon forming a part of this application in which, Figure 1 is a bottom plan view of my turntable showing portions broken away to amplify the illustrations; Figure 2 is a sectional view thereof taken from the line 2—2 of Figure 1; Figure 3 is a fragmentary top or plan view of my turntable; Figure 4 is an enlarged fragmentary sectional view taken from the line 4—4 of Figure 1; Fig. 5 is an enlarged fragmentary sectional view, taken from the line 5—5 of Fig. 4, showing the clutch mechanism of my turntable, and Fig. 6 is a fragmentary sectional view, taken from the line 6—6 of Fig. 2.

2

Similar characters of reference refer to similar parts and portions throughout the several views of the drawings.

The base 1, turntable frame 2; wheel tracks 3; indexing latch 4; rollers 5 and 6; shafts 7 and 8; synchronizing gears 9 and 10; idler gears 11 and 12; worm gears 13 and 14; worm wheels 15 and 16; gear 17; ring gear 18; bevel gears 19 and 20; clutch members 21 and 22; clutch shafts 23 and 24; clutch operating bracket 25; clutch operating lever 26; clutch operating spring 27; stop members 28; wheels 29 and the axle 30 constitute the principle parts and portions of my turntable.

The base 1 is a substantially disc shaped plate preferably disposed in horizontal flat condition as shown best in Figure 2 of the drawings. It will be noted that this base 1 may be varied in construction without altering the mechanical operation of my turntable. The turntable frame 2 is a substantially flat disc shape plate arranged to support the major portion of the operating mechanism of my turntable. Secured on the upper part of the turntable frame 2 is a pair of substantially U-shaped in cross section wheel tracks 3 arranged to guide the wheels of the vehicle in alignment with the rollers 5 and 6. The cross sectional shape of these wheel tracks 3 is best shown in Figure 4 of the drawings in alignment with the roller 5. These rollers 5 and 6 are fixed on the shafts 7 and 8 respectively on which the synchronizing gears 9 and 10 respectively are secured intermeshing with the idler gears 12 and 11 respectively for synchronizing the operation of the shafts 8 with each other and the shafts 7 with each other. These shafts 7 and 8 are secured to the turntable frame 2 by bearings 7a and 8a respectively. Secured on one of the shafts 8 is the worm gear 13 meshing with the worm wheel 16 on the square in cross section clutch shaft 24 revolvably mounted in the brackets 24a at its opposite ends, said bracket being secured to the turntable. Slidably mounted on the square in cross section clutch shaft 24 is the bevel gear 20. This bevel gear 20 is provided with an annular groove 20a engaged by the clutch operating bracket 25. At one side of the annular groove portion 20a is a clutch engaging portion 20b preferably integral with the bevel gear 20 and arranged to engage the clutch member 21. It will be noted that the clutch members 21 and 22 are of similar form and are secured to the turntable frame 2. As shown in Figure 4 of the drawings, the clutch member 22 is provided with a pair of teeth 22a engageable with the clutch engaging teeth 19a of the bevel gear 19. This bevel gear 19 is provided with an

annular groove 19b engaged with the clutch operating bracket 25, all as shown best in Figure 1 of the drawings. The clutch shaft 23 is square in cross section as shown in Figure 4 of the drawings and is substantially identical to the clutch shaft 24 and is revolvably mounted at its opposite ends in bracket members 23a secured to the turntable frame 2. The gear 17 is secured on the clutch shaft 23 and meshes with the gear 15 revolvably mounted in brackets 23a and 15a as shown in Figure 1 of the drawings. This gear 15 is in the form of a worm wheel and meshes with the worm gear 14 on one of the shafts 7 as shown best in Figure 4 of the drawings. Secured on the shafts 7 near opposite ends are the rollers 5, adapted to engage the driving wheels of a vehicle. Fixed on the shafts 7 are the synchronizing gears 9 intermeshed with the idler gear 12 arranged to synchronize the revoluble operation of the shafts 1. Secured on the base 1 is the ring gear 18 adapted to mesh with the bevel gears 19 and 20 supported by the turntable frame 2. The clutch operating bracket 25 is reciprocally mounted on the axis of the clutch shafts 23 and 24 and is arranged to be shifted longitudinally thereof, carrying the gears 19 and 20 alternately into and out of mesh with the ring gear 18. This clutch operating bracket 25 is substantially rectangular in form and is provided with slotted bearing portions 25a in which screws 25b are positioned. It will be noted that the slotted portions 25a are parallel to the axis of the clutch shafts 23 and 24 permitting reciprocation of the clutch operating bracket 25 about the screws 25b all as shown best in Figure 1 of the drawings. As shown in Figure 2 of the drawings the clutch operating bracket 25 is provided with finger portions 25c extending downwardly and into engagement with the annular groove portions 19b and 20a of the bevel gears 19 and 20 respectively. The turntable frame 2 is provided with a hollow cylindrical sleeve portion 30a engaging the outer side of the axle 30 secured to the base 1 about which the turntable frame 2 rotates, as shown best in Figure 1 of the drawings. The clutch operating lever 26 is pivotally mounted on the bolt 26a secured to the turntable frame 2. The clutch operating spring 27 is secured to the hub 30a of the turntable frame 2. The opposite end of this spring 27 is connected with the clutch operating lever 26 outwardly of the axis of the bolt 26a whereby the pivotal movement of the lever 26 causes the axis of the spring 27 to pass the axis of the bolt 26a tending to force the lever 26 in the opposite direction. As shown in Figure 1 of the drawings, this clutch operating lever 26 is T-shaped and is provided with an arcuate slotted portion 26b engaged by a pin 25c secured to the clutch operating bracket 25. The clutch operating lever 26 is provided with a laterally offset portion 26c extending into adjacent relation with the base plate 1 on which the stop members 28 are positioned substantially 180° from each other thereon arranged to limit movement of the clutch operating lever 26 when the turntable frame 2 is moved around the axis of the axle 30. The wheels 29 are supported on the turntable frame 2 by brackets 29a secured thereto. These wheels 29 bear upon the base 1 and support the turntable frame 2 in spaced relation with the base 1 as shown best in Figures 1 and 2 of the drawings. The indexing latch 4 is provided with an engaging roller 4a engageable with notched portions 2a and 2b in the periphery of the turntable frame 2 substantially 180° apart. The lower end 75

of the indexing latch 4 is pivotally connected with the base 1 by means of a pin 4b and is engaged by the spring 4c tending to maintain the roller 4a in engaged relation with the turntable frame 2 at its periphery. This indexing latch 4 is provided with an upwardly extending vehicle engaging portion 4d arranged to engage the bumper or other portion of the vehicle for releasing the roller from one of the notches 2a or 2b of the turntable frame 2. It will be noted that the base 1 remains in stationary position and that the indexing latch 4 is stationarily secured thereto.

The operation of my turntable is substantially as follows: When an automobile is driven upon by turntable toward the indexing latch 4 with the wheels of the vehicle in alignment with the tracks 3 the bumper or other fixture in connection with the automobile pivots the indexing latch 4 out of engagement with the turntable frame 2 and the driving wheels of the vehicle engage the rollers 5 or 6 as the case may be for operating the turntable. As shown in Figures 2 and 3 of the drawings a vehicle approaching the indexing latch 4 and having rear driving wheels proceeds until the indexing latch 4 is disengaged as hereinbefore described, whereupon the rear driving wheels engage the rollers 5. As the power is continually applied to the driving wheel of the vehicle, the rollers 5 are rotated together with the synchronizing gears 9 and idler gear 12. It is noted that the rollers 5 and 6 are each provided with arcuate in cross section annular peripheral portions adapted to engage the tires of the vehicle wheels. When the shafts 7 of the rollers 5 and the gears 9 are rotated, the worm gear 14 on one of the shafts 7 in mesh with the worm wheel 15 causes rotation of the gear 17 enmeshed therewith together with the shaft 23 and bevel gear 19 enmeshed with the ring gear 18 secured on the base 1. As shown in Figure 2 of the drawings, the bevel gear 19 is engaged with the ring gear 18 whereby the turntable frame 2 is propelled about the axis of the axle 30 by rotative operation of the bevel gear 19. As the turntable frame 2 rotates about the axis of the axle 30, the notched portion 2b is rotated to a position corresponding to the notched portion 2a as shown in Figure 3 of the drawings, whereupon the clutch operating lever 26 engages one of the stop members 28, shifting the lever 26 until the axis of the spring 27 passes over the axis of the bolt 26a whereupon the tension of the spring forces the lever 26 in the opposite direction engaging the pin 25c on the clutch operating bracket 25 in the opposite end of the arcuate slotted portion 26b slidably shifting the bevel gears 19 and 20 longitudinally of the rectangular in cross-section shafts 23 and 24 whereby the bevel gear 19 is disengaged from ring gear 18 and the bevel gear 20 is engaged therewith and freely rotatable intermediate the fingers 25c of the clutch shifting bracket 25 in the annular grooved portion 20a of the gear 20. It will be noted that the notched portion 2a of the turntable frame 2 is then engaged with the roller 4a of the indexing latch 4 whereupon vehicles may be driven onto the rollers 5 and 6 whereby the driving wheels of the vehicle rest upon the rollers 6. During operation of the rollers 6 the turntable frame 2 is operated in the reversed direction until the clutch shifting lever 26 contacts one of the stops 28 and shifts the clutch operating bracket so that the bevel gear 19 is again enmeshed with the ring gear 18 and the bevel gear 20 is out of mesh therewith. Thus

each successive rotative operation of the turntable frame 2 is in the opposite direction and each rotative operation is limited to 180° and automatically interrupted by contact of the clutch operating lever 26 with one of the stops 28. It will be noted that the worm wheel 16 in mesh with the worm gear 13 on one of the shafts 6 is provided for operating the turntable frame 2 in one direction. The worm wheel 16 enmeshed with the gear 17 causes reversal of this directional operation when the rollers 5 and the shafts 7 are rotated providing for a reversal of the rotative direction of the turntable frame 2 with each successive operation thereof through 180°. It will be here noted that a vehicle may be driven on the turntable frame 2 and engaged with the indexing latch 4 whereupon continued operation of the vehicle driving wheel causes the turntable frame 2 to automatically rotate 180° whereupon the rollers engaged with the vehicle driving wheels are automatically locked when the clutch shifting bracket is actuated by the lever 26 permitting the driving wheels of the vehicle to force the vehicle off the turntable frame 2 in the opposite direction of travel. With each reciprocating operation of the clutch operating bracket 25, one of the gears 19 or 20 is disengaged from the ring gear 18 and the clutch portions thereof engaged with one of the clutch members 21 or 22, for example, when the bevel gear 20 is disengaged from the ring gear 18 the clutch portions 29b are automatically engaged with the clutch member 21, limiting operation of the rollers 6 and permitting the driving wheels of the vehicle to gain traction thereon for forcing the vehicle longitudinally of the tracks 3 and off from the turntable frame 2. Thus engagement of the clutch member 21 and 22 with the bevel gears 20 and 19 respectfully occurs in order to lock the vehicle wheel engaging rollers when the turntable frame 2 has completed 180° of rotational movement about the axis of the axle 30.

Though I have shown and described the particular construction, combination and arrangements of parts and portions, I do not wish to be limited to the particular construction, combination and arrangement but desire to include in the scope of my invention the construction, combination and arrangement as substantially set forth in the appended claims.

Having thus described my invention, what I claim as new and desire to secure by Letters Patent is:

1. In a turntable of the class described, the combination of a base and a turntable frame wheels for supporting said frame on said base, axle means at the middle of said base and turntable frame for controlling rotative operation of said turntable frame about said base, vehicle engaging rollers adapted to engage the driving wheels of a vehicle at the upper side of said turntable frame, gear means driven by said vehicle engaging rollers, a ring gear mounted on said base concentric with the turntable frame and adapted to be engaged by said gear means, clutch means mounted on said turntable frame and connected with said gear means, a clutch shifting bracket engaging said clutches and said gears reciprocally mounted on the lower side of said turntable frame, a clutch shifting lever engageable with said clutch shifting bracket and stop means on said base engageable with said lever when forced thereagainst by movement of said turntable relative to said base for shifting said clutch operating bracket and said gear means into

and out of engagement with said ring gear and said clutch means whereby movement of said lever and said clutch shifting bracket causes one of said clutches to be engaged while the other clutch is disengaged and causes the gear adjacent the disengaged clutch to be meshed with said ring gear.

2. In a turntable of the class described, the combination of a rotary turntable frame wheels for supporting said frame, vehicle wheel engaging rollers revolvably mounted on said turntable frame, gear means operatively connected with said rollers, a base, a ring gear fixed on said base engageable with said gear means, clutch means on said turntable frame engageable with said gear means for limiting rotation thereof, stop means fixed on said base, a clutch shifting lever pivotally connected with said turntable frame and engageable with said stop means when forced thereagainst by movement of said turntable relative to said base for shifting said gear means out of engagement with said clutch means and into engagement with said ring gear.

3. In a turntable of the class described, the combination of a base, a ring gear on said base, a turntable frame rotatably mounted above said base, wheels for supporting said frame on said base, the first vehicle engaging rollers at one side of said ring gear and second vehicle engaging rollers at the opposite side of said ring gear connected with said turntable frame, gear means operatively connected to said first and second wheel engaging rollers engageable with said ring gear in a forward relation to each other, clutch means on said turntable frame engageable with said gear means at opposite sides of said ring gear for limiting rotation thereof, a clutch operating frame reciprocally mounted on said turntable frame and engaging said gear means for shifting the same individually in and out of engagement with said ring gear, stop means on said base, a trip lever on said turntable engaging said clutch operating frame, and engageable with said stop means when said turntable moves relative to said base, for reciprocating said clutch operating frame said gear means connected individually at opposite ends of said clutch operating frame whereby reciprocal movement of said clutch operating frame in one direction engages said gear means with said ring gear in operative relation with said first vehicle wheel engaging rollers and disengages the gear means at its opposite end from the ring gear and engages said gear means with said clutch means for limiting the rotational operation of said second vehicle wheel engaging rollers.

4. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually clutch means connected with each of said pair of gears and clutch means in connection with said turntable frame engageable with each of said pair of gears, stop means on said base, a trip lever on said turntable engaging said clutch operating frame, and engageable with said stop means when said turntable moves relative to said base for reciprocating said clutch operating frame whereby reciprocal operation of said clutch operating bracket engages one of said gears with said ring gear and engages the

other said pair of gears with said clutch means on said turntable frame.

5. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and clutch means on said turntable frame engageable with each of said pair of gears, stop means on said base, a trip lever on said turntable engaging said clutch operating frame, and engageable with said stop means when said turntable moves relative to said base for reciprocating said clutch operating frame whereby reciprocal operation of said clutch operating bracket engages one of said gears with said ring gear and engages the other of said pair of gears with said clutch means on said turntable frame, vehicle wheel engaging rollers operatively connected with each of said pair of gears.

6. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and clutch means on said turntable frame engageable with each of said pair of gears, stop means on said base whereby reciprocal operation of said clutch operating bracket engages one of said gears with said ring gear and engages the other of said pair of gears with said clutch means on said turntable frame, vehicle wheel engaging rollers, operatively connected with each of said pair of gears, a clutch shifting lever pivotally connected with said turntable, said stop means substantially 180° apart on said base engageable with said clutch operating lever for reciprocally shifting said clutch operating bracket.

7. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and clutch means on said turntable frame engageable with each of said pair of gears, stop means on said base whereby reciprocal operation of said clutch operating bracket engages one of said gears with said ring gear and engages the other of said pair of gears with said clutch means on said turntable frame, vehicle wheel engaging rollers, operatively connected with each of said pair of gears; a clutch shifting lever pivotally connected with said turntable, said stop means substantially 180° apart on said base engageable with said clutch operating lever for reciprocally shifting said clutch operating bracket, a spring connected with said turntable frame and said clutch operating lever arranged to pass over the pivotal axis thereof for exerting tension over the axis of said clutch operating lever for pivotally moving the same together with said clutch operating bracket.

8. In a turntable of the class described, the combination of a turntable frame, a base there-

for wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and clutch means on said turntable frame engageable with each of said pair of gears, stop means on said base whereby reciprocal operation of said clutch operating bracket engages one of said gears with said ring gear and engages the other of said pair of gears with said clutch means on said turntable frame, vehicle wheel engaging rollers operatively connected with each of said pair of gears; a clutch shifting lever pivotally connected with said turntable, said stop means substantially 180° apart in connection with said base engageable with said clutch operating lever for reciprocally shifting said clutch operating bracket, a spring connected with said turntable frame and said clutch operating lever arranged to pass over the pivotal axis thereof for exerting tension over the axis of said clutch operating lever for pivotally moving the same together with said clutch operating bracket, said clutch operating lever having an arcuate slotted portion therein at one end, said clutch operating bracket having a bearing portion engageable with said clutch operating lever.

9. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and clutch means on said turntable frame engageable with each of said pair of gears, stop means on said base whereby reciprocal operation of said clutch operating bracket engages one of said gears with said ring gear and engages the other of said pair of gears with said clutch means on said turntable frame, vehicle wheel engaging rollers, operatively connected with each of said pair of gears; a clutch shifting lever pivotally connected with said turntable, said stop means substantially 180° apart on said base engageable with said clutch operating lever for reciprocally shifting said clutch operating bracket, a spring connected with said turntable frame and said clutch operating lever arranged to pass over the pivotal axis thereof for exerting tension over the axis of said clutch operating lever for pivotally moving the same together with said clutch operating bracket, said clutch operating lever having an arcuate slotted portion therein at one end, said clutch operating bracket having a bearing portion engageable with said clutch operating lever, an indexing latch pivotally connected with said base and engageable with said turntable frame at its periphery and extending above said turntable frame adapted to be engaged by a vehicle on the upper side of said turntable frame.

10. In a turntable of the class described, the combination of a turntable frame, a base therefor wheels for supporting said frame on said base, a ring gear on said base, a clutch operating bracket reciprocally mounted on said turntable frame, a pair of gears connected with said clutch operating bracket, each adapted to engage said ring gear individually, clutch means connected with each of said pair of gears and a clutch means on said turntable frame engage-

able with each of said pair of gears, stop means on said base whereby reciprocal operation of said clutch operating bracket engages one of said gears with said ring gear and engages the other of said pair of gears with said clutch means on said turntable frame vehicle wheel engaging rollers operatively connected with each of said pair of gears, a clutch shifting lever pivotally connected with said turntable, said stop means substantially 180° apart on said base engageable with said clutch operating lever for reciprocally shifting said clutch operating bracket, a spring connected with said turntable frame and said clutch operating lever arranged to pass over the pivotal axis thereof for exerting tension over the axis of said clutch operating lever for pivotally moving the same together with said clutch operating bracket, said clutch operating lever having an arcuate slotted portion therein at one end, said clutch operating bracket having a bearing portion engageable with said clutch operating lever, an indexing latch pivotally connected with said base and engageable with said turntable frame at its periphery and extending above said turntable frame adapted to be engaged by a vehicle on the upper side of said turntable frame,

said turntable frame having notched portions therein at its periphery engageable with said indexing latch member.

FRANK C. POYNER.
